LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

FLUID-OPERATED PERCUSSIVE TOOL.

1,096,987.

Specification of Letters Patent.

Patented May 19, 1914.

Application filed February 26, 1914. Serial No. 821,149.

To all whom it may concern:

Be it known that I, LEWIS C. BAYLES, a citizen of the United States, residing at Easton, in the county of Northampton and State of Pennsylvania, have invented a certain new and useful Improvement in Fluid-Operated Percussive Tools, (Case C,) of which the following is a specification.

This invention relates to fluid operated percussive tools and more particularly to tools of the type wherein the admission of fluid is controlled directly by the movement of the piston.

The object of the present invention is to provide means for controlling admission of fluid to one end of the cylinder so that the passage for conveying the fluid, although ultimately controlled by the piston, will remain open for a greater portion of the return stroke than of the forward stroke.

This object is accomplished by the invention, a practical embodiment of which is shown in the accompanying drawings in which—

Figures 1 and 2 are longitudinal sections showing the piston and the auxiliary controlling valve in different positions.

In the drawings is shown a drill having a cylinder 1 which consists of a smaller rearward bore 2 and a larger forward bore 3 in which slides a piston 4 having an enlarged piston head 5 sliding in the forward bore and a shank 6 sliding in the rearward bore, there being a neck 7 of smaller diameter than the shank 6 between the head and the shank. The operating fluid is admitted to the rearward end of the smaller bore 2 by an inlet passage 8 and thus exerts a constant pressure against the rear face of the shank 6 of the piston. Leading from this constant pressure portion of the cylinder to the extreme forward end of the cylinder is a passage 9 for conveying fluid to accomplish the return stroke of the piston. This passage 9 has two ports leading from the constant pressure portion of the cylinder. The rearward port 10 is so placed that it is uncovered by the piston soon after the piston has passed the median point of its forward stroke. The forward port 11 is not uncovered until the piston is practically at the forward end of its stroke. The port 11 opens directly into the passage 9 whereas there is an auxiliary valve 12 for controlling the port 10. This valve 12 slides in a valve

chest 13 on the side of the cylinder and has a forward operating face exposed to the pressure of fluid in passage 9 and a rearward operating face which is exposed to the pressure of the fluid in the rear end of the cylinder bore 3 by means of a passage 14 which leads therefrom to the rear end of the valve chest 13. The rear end of the bore 3 is intermittently supplied with fluid pressure by means of a passage 15 which leads from the inlet 8 to a point near the forward end of the bore 2 so positioned as to be put into communication with the rear end of bore 3 near the end of the rearward stroke of the piston by reason of the neck 7 of the piston. An exhaust port 16 is provided for the intermittently supplied parts of the cylinder, being uncovered by the forward part of the piston near the end of its rearward stroke and after the port 10 has been closed by the piston; and again uncovered by the rear end of the piston near the forward end of its stroke after the passage 15 has been closed.

In operation, supposing the parts to be in the positions shown in Fig. 2, the operating fluid is being admitted by the inlet passage 8 to the constant pressure portion of the cylinder and also through the passage 15 to the rear end of the bore 3 so that there is pressure being exerted on the rear face of the piston head and on the rear face of the shank 6. In this position of the piston live fluid passes through passage 14 so that there is pressure on the rear operating surface of the valve 12 and atmospheric pressure on the forward operating surface of the valve 12 by reason of the fact that the forward end of the cylinder and the passage 9 are open to atmosphere through the exhaust port 16. The valve 12 will therefore be in its forward position closing the port 10. The pressure of the fluid on the rear surfaces of the piston will drive it forward, the fluid in the bore 3 acting expansively after the passage 15 is cut off. By reason of the fact that the port 10 is closed by valve 12 no fluid will be admitted into the front end of the cylinder until the rear face of the piston shank 6 has uncovered the port 11. This will admit fluid pressure to the passage 9. The first effect of admission of this pressure to the passage 9 will be to drive the valve 12 rearward there being no pressure on the rearward operating face of the valve 12 on account of the fact that the rear end of the bore 3 is open

- to atmosphere through the port 16. The opening of the port 10 will allow fluid to pass to the forward end of the cylinder through both ports 10 and 11 but as the port 5 10 is not covered by the piston until the piston has traveled a considerable part of its rearward stroke, the admission to the front end of the cylinder will continue for a considerably longer period during the backward stroke of the piston than during its forward stroke.
- The object of this construction is that although the fluid is admitted to the forward end of the cylinder through the port 10 for the same period of the backward stroke as it would be if there were no valve 12 and thus a full return stroke of the piston is obtained, no fluid is admitted to the forward end of the cylinder during the forward 15 stroke of the piston until it has reached approximately the forward end of its stroke so that a heavy uncushioned blow of the piston is obtained without any increase of fluid consumption.
- 20 It is to be understood that the present showing and description discloses only one specified modification of my invention and other forms and modifications are included in the spirit and scope of the claims.
- 25 What I claim is:
1. In a percussive tool, a cylinder, a piston, means for constantly admitting fluid to one end of the cylinder, a passage from said constant pressure end of the cylinder to the opposite end, said passage having a port opening into the constant pressure end uncovered by the piston near the end of its stroke, a valve closing said port and having an operating surface exposed to the pressure in said passage, and a second port opening to said passage from said constant pressure cylinder end, said second port being uncovered by the piston at a later point in its stroke than said first port and serving to 30 admit pressure to said passage against said valve operating surface to open said first port.
  2. In a percussive tool, a cylinder, a piston in said cylinder having two small rearward 35 surfaces and a large forward surface, means for admitting pressure constantly to a part of the cylinder to exert pressure on one of said rearward surfaces, and means for exerting intermittent pressure on the other of said rearward surfaces and on said forward surface, the means for exerting pressure on said forward surface comprising a passage leading to the forward end of the cylinder and having a rearward port and a forward 40 port opening into said constant pressure part of the cylinder and positioned to be consecutively uncovered by the piston, and a valve adapted to close the rearward port during the forward stroke and prevent fluid from 45 entering said passage, said valve having an

operative surface exposed to the pressure in said passage and serving to move it to open said rearward port when pressure is admitted to said passage through said forward port.

3. In a percussive tool, a cylinder, a piston having two surfaces for driving it in one direction and one surface for driving it in the other direction, means for admitting fluid to the cylinder to exert a constant pressure on one of the first mentioned surfaces, passages controlled by the piston for admitting and exhausting pressure in the cylinder to exert an intermittent pressure on the second of said surfaces, and means for exerting intermittent pressure on the third surface comprising passages controlled by the piston, and a valve having operative surfaces exposed to the pressure on said intermittently supplied surfaces.

4. In a percussive tool, a cylinder, a piston in said cylinder having two pressure surfaces for operating it in one direction and one larger surface for operating it in the other direction, means for admitting pressure constantly to the cylinder to be exerted on one of said smaller pressure surfaces, a passage for conveying fluid from the constant pressure part of the cylinder to the opposite end of the cylinder to be exerted against said larger surface, the said passage having a port from said constant pressure part uncovered by the piston near the end of its forward stroke, a valve closing said port and having operative surfaces, a second port from said constant pressure part adapted to be uncovered by said piston at a later period of its stroke and to admit pressure to an operating surface of said valve to open said first port, means to admit pressure to another part of the cylinder to be exerted against the other of said smaller surfaces during the forward stroke of the piston, a passage from said other part of the cylinder to an operating surface of said valve opposed to said first operating surface and exhaust passages for the intermittently supplied portions of the cylinder.

5. In a percussive tool, a cylinder, means for constantly admitting pressure to one end of the cylinder, a passage from said constant pressure end of the cylinder to the opposite end, said passage having a port opening into said constant pressure end uncovered by the piston near the end of its stroke, a valve for closing said port during the forward stroke of the piston, said valve having an operating surface for moving it to open said port, a second port opening from said constant pressure end and uncovered by said piston at a later point in its stroke, said port serving to convey fluid pressure to said valve operating surface, and means to move said valve to close said first port on the reverse stroke of the piston.

6. In a percussive tool, a cylinder, a piston in said cylinder having two pressure surfaces for operating it in one direction and one larger surface for operating it in the other direction, means for admitting pressure constantly to the cylinder to be exerted on one of said smaller pressure surfaces, a passage for conveying fluid from the constant pressure part of the cylinder to the opposite end of the cylinder to be exerted against said larger surface, the said passage having a port from said constant pressure part uncovered by the piston near the end of its forward stroke, a valve closing said port and having operative surfaces, a second port from said constant pressure part

adapted to be uncovered by said piston at a later period of its stroke and to admit pressure to an operating surface of said valve to open said first port, a passage controlled by the piston for admitting pressure to the other of said smaller surfaces, during part of the forward stroke, and means to admit pressure to the opposed operating surface of the valve to close said port on the back stroke of the piston.

In testimony whereof, I have hereunto set my hand.

LEWIS C. BAYLES.
